UNITED STATES PATENT OFFICE.

JAMES REED, OF EAGLE, MICHIGAN.

WASHING-MACHINE.

SPECIFICATION forming part of Letters Patent No. 508,756, dated November 14, 1893.

Application filed July 1, 1892. Serial No. 438,684. (No model.)

To all whom it may concern:

Be it known that I, JAMES REED, a citizen of the United States, residing at Eagle, in the county of Clinton and State of Michigan, have 5 invented certain new and useful Improvements in Washing-Machines, of which the following is a specification, reference being had therein to the accompanying drawings.

This invention relates to a new and useful 10 improvement in washing machines and the invention consists in the peculiar arrangement, construction and combination of the various parts all as more fully hereinafter described.

15 In the drawings, Figure 1 is a front elevation of my improved device. Fig. 2 is a side elevation thereof showing the cover raised. Fig. 3 is a vertical, central, longitudinal section through Fig. 1. Fig. 4 is a central cross 20 section on line $\alpha\alpha$ of Fig. 3. Fig. 5 is a detached perspective view of the tub. Fig. 6 is an enlarged section through one of the pounders.

A are the supporting legs which support a 25 box shaped body formed of sides B and ends C. This box shaped body is preferably rectangular in cross section and within it is the tub D, preferably of sheet metal connected and supported at its upper edge by an exterior 30 frame E which rests upon the upper edge of the box, as shown in Fig. 3.

F is the top which at its rear edge is provided with hinges G having the straps H extending below its lower edge and loosely engaging in the sockets H' formed on the frame 35 E of the tub. Thus the top is hinged to the tub or frame E and at the same time is detachable therefrom by drawing the strap H out of socket of H'. When the top is turned 40 upon the hinges to its open position, as shown in Fig. 4 it is held from falling backward by the brace I detachably secured at its upper end to the edge of a flange or apron I² which extends around the four sides of and 45 is secured on the top, the lower end of the brace being attached to the side of the tub D near the front. The top is provided with a cover I' having a central supporting brace I² in its open position, as shown in Fig. 2 the

lower end of the brace being secured to a 50 cross bar L in the top. The top is provided interiorly with a rectangular frame G' in which is journaled a series of crank shafts J extending from end to end of the top and at one end, outside of the top, are provided 55 with the intermeshing gear wheels K, one of which is provided with a crank K', by means of which a rotary motion may be imparted to all the shafts simultaneously. Each crank of these shafts is provided with a pounder or 60 dasher, preferably of the construction shown in Fig. 6, and consisting of the inverted cone shaped body a having a cylinder b extending through its upper end, and within the body a having a reinforcing flange c, having its 65 lower end connected with the interior of the body, as plainly shown in Fig. 6.

In the cylinder or tube b is a supporting shank d secured in any suitable manner, and at its upper end provided with a detachably 70 bearing block e which is clamped by means of bolts f upon the crank of the shaft, a suitable packing g being interposed. The crank shaft passes through the cross bar L which forms a central bearing for the shafts. The 75 cross bar may be made in two parts, grooved on the upper and lower edges respectively so that the shafts may be readily placed therein. It is evident thus far that if the top is down, the parts being in the position shown in Fig. 80 3, motion being imparted to the crank K', all the crank shafts will be rotated and the pounders will be rapidly raised or lowered, approaching and receding from the bottom of the tub, upon which the clothes rest. 85

I preferably employ a false bottom M of wire netting of other suitably perforated material. This false bottom M is secured to the frame N' which rests upon the bottom of the tub D. 90

In case the top should raise or lower more or less by the force of the blows of the pounders upon the clothes this will be taken up by the sliding movement between the strap of the hinges and the socket H' on the tub, so 95 that the top will not be displaced in operation.

The cover being closed it may be locked in position by the turn button M'. To put the

clothes in, the top is turned upon the hinge as shown in Fig. 4, cross-bars M^2 being arranged between each series of pounders, secured to the lower edge of flange or apron I^3 depending from the sides of the cover F preventing their being displaced when the top is in this position. The apron I^3 forms a rigid support for the bars M^2 , also assists in holding the cover in place and in conducting drip 10 into the tub past the joint between the cover and tub.

The top may be removed when desired by disengaging the upper end of the brace I from the top and lifting the strap H from the 15 socket H' . The tub is provided with suitable handles N at its ends, by means of which it may be lifted from the box shaped body and if desired placed upon the stove or carried to any desired point. It is provided with 20 a suitable exit aperture, controlled by the stopper or plug O .

O' is a frame slidingly engaging in suitable bearings in the end of the box shaped body beneath the tub and provided at one end with 25 legs P secured thereto. This frame may be drawn out as shown in Fig. 1 to support an ordinary tub or clothes basket, or when not in use this may be pushed into the body, as shown in Fig. 3. The frame is provided with 30 the cross piece O^2 extending out beyond the frame on opposite sides and resting on the cleats O^3 secured to the sides B of the box.

Q is an end extension on the body, having a cross bar Q' which forms the wringer board 35 at one end of the tub.

R is an over-hanging guard at one end of the top which protects the gear wheel and

prevents possibility of the clothes being caught therein.

What I claim as my invention is—

1. A washing machine consisting of a rectangular supporting body, a tub within the body, having an exterior frame E resting on the upper edges of the body, a false bottom for the tub consisting of foraminous material, 45 a top F having a detachable connection with the frame E , a depending flange on the top extending into the tub, cross bars M^2 connected to the lower edge of the flange, a brace connected to the side of the tub and the depending flange for supporting the top in an open position, a series of crank shafts mounted in the top, intermeshing gears on the crank shafts, a crank on one shaft and a hinged cover for the top, substantially as described. 55

2. In a washing machine, the combination with the supporting body, of a top hinged thereto, said hinge having a detachable engagement with the tub, of the series of crank shafts mounted in the top, intermeshing gears 60 K on the shafts, the crank K' on one shaft, the pounders pivoted to the cranks, the fixed cross bars M^2 between the rows of pounders, the supporting strap I , detachably engaging at its upper end with the top, the cover I' and 65 the supporting strap I^2 , substantially as described.

In testimony whereof I affix my signature in presence of two witnesses.

JAMES REED.
